UNITED STATES PATENT OFFICE.

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

ELECTRIC GOVERNOR SWITCH.

Original application filed June 16, 1922, Serial No. 568,714. Divided and this application filed May 28, 1923. Serial No. 641,903.

This invention relates to electric pump governors and the principal object of the invention is to provide an improved pump governor of the type shown in Patent No. 5 1,169,305 of Walter V. Turner, dated January 25, 1916.

This case is a division of my original application, Serial No. 568,714, filed June 16, 1922.

10 In the accompanying drawing, Fig. 1 is a central sectional view of an electric pump governor embodying my improvements, and Fig. 2 a section on the line 2—2 of Fig. 1.

As shown in the drawing, the electric pump governor may comprise a pipe bracket 1 to which is applied a casing 2. Said casing contains a cylindrical bushing 3 forming a piston chamber 4 for a switch piston 5 having a cored stem 6 carrying at the outer 20 end connected switch contacts 7.

For controlling the operation of the piston 5, a regulating device is provided comprising a cut-in and a cut-out portion, the cut-in portion comprising a piston 8 carrying a valve 9 and subject to the pressure of an adjustable coil spring 10. The cut-out portion may comprise a piston 11 having a valve 12 and subject to the pressure of an adjustable coil spring 13.

25 Before describing the particular improvements involved in the construction I will describe the general operation of the governor.

Assuming the springs 13 and 10 to have been adjusted to the respective desired cutting out and cutting in pressures and that the compressor is running, the pressure of fluid compressed by the compressor which is delivered to the usual main reservoir and 30 which I will hereinafter term the main reservoir pressure, is supplied to the seated area of the valve 12 as well as to the seated area of the valve 9 through pipe 14, passage 15, chamber 16, to passage 18, and thence to passage 19, which leads to the seated areas of said valves.

When the main reservoir pressure acting on the seated area of the cut-out valve 12, slightly exceeds the pressure of the spring 13, the valve 12 will be lifted from its seat, exposing the full area of the piston 11 to main reservoir pressure, thus causing a quick positive opening movement thereof. With the valve 12 open, main reservoir pres-

sure is supplied through passage 20 to the outer area of the cut-in piston 8 and since main reservoir pressure now acts on the full area of the piston 8, the seated area of the valve 9 having been previously subject to main reservoir pressure, the piston 8 will be instantly shifted to its upper seat 21, closing communication through passage 22 from switch piston chamber 4 to the atmosphere and opening communication for supplying fluid at main reservoir pressure 65 to piston chamber 4 through port 23 and passage 22.

The main reservoir pressure acting on switch piston 5 then shifts the piston so as to break the circuit of the compressor motor 70 by separating the contacts 7 from the contacts 24 which are in circuit with the motor. At the same time, fluid at main reservoir pressure is supplied through port 25 in piston 5 to the opposite side of the piston and 75 flows through port 26 into the hollow stem 6. When the piston 5 is shifted, ports 27 are uncovered by the movement of the stem 6, as the contacts 7 separate from the contacts 24, thus directing a stream of air onto 80 the separating contacts to serve as a pneumatic arc blowout. When the piston 5 completes its outward travel, the annular bead 28 on the piston 5 engages a seat 47, thus preventing the further escape of main 85 reservoir pressure.

Movement of the piston 5 to its cut-out position also uncovers port 29, so that fluid at main reservoir pressure is supplied through passage 30 to the spring chamber 90 31 of the cutout portion of the governor. Fluid pressures on opposite sides of piston 11 being thus equalized, the spring 13 will act to return the piston 11 and valve 12 to its seat. After the valve 12 seats, main 95 reservoir pressure will continue to be supplied to the piston chamber 4 through passage 19, past the open valve 9 and through port 23 and passage 22.

The switch piston therefore remains in its 100 cut-out position until the main reservoir pressure reduces to a point slightly less than the pressure of the spring 10 and then the cut-in piston 8 moves to its position seating the valve 9. This closes communication through which fluid at main reservoir pressure is supplied to the switch piston 5 and at the same time the piston chamber 105

4 is connected to the atmosphere, through passage 22, spring chamber 32 and exhaust passage 33. Spring 34 then returns the piston 5 to its cut-in position, in which the contacts 7 engage the contacts 24 and close the circuit of the motor which operates the compressor. At the same time, the spring chamber 31 is connected to the atmosphere through passage 30, passage 35, spring chamber 32 and passage 33. The piston 11 is therefore held to its seat at this time only by the pressure of the spring 13, so that the cut out valve 12 can now lift from its seat whenever the main reservoir pressure slightly exceeds the pressure of the regulating spring 13.

In order to adjust the tension of the springs 10 and 13, each spring contains a rod 36 having screw threads for an adjusting nut 37. Said nut is made lobe shaped as shown in Fig. 2, so that the nut cannot rotate when the rod 36 is turned. Each rod is provided with a collar 38 adapted to make a leak tight seat within the spring chamber 25 and a screw threaded extension of each rod is provided with a nut 39. The tension of the regulating spring is externally adjusted by loosening the nut 39 and turning the rod 36 by means of a screw driver inserted in the slot 40.

As the rod is turned, the adjusting nut 37 moves up or down according to the direction in which the rod is turned and the tension of the regulating spring is thus varied as desired. When the desired adjustment is secured, the nut 39 is screwed down to firmly hold the rod 36 and nut 37 in the adjusted position and at the same time makes a leak tight joint at the collar 38.

A separate valve seat section 41 is provided for the valve 12 and a separate valve seat portion 42 is provided for the valve 9, so that maintenance is facilitated by providing for quick removal for cleaning and replacing worn or damaged valve seats.

Screws 46 serve to hold the seat sections 41 and 42 in place, said screws being oppositely disposed but not diametrically opposite, so that each seat can only be replaced in a particular position of adjustment as determined by the screws 46.

Each contact 24 is connected to and supported by a spring 43, a projection 44 of the spring serving as a stop to limit lateral movement of the contact and a stop 45 being provided to limit the vertical movement thereof. While providing the desired flexibility, the above contact construction prevents the contact fingers 7 from "catching" when cutting in.

When the switch contact portion of the electric compressor governor is enclosed by the usual hood (not shown) it has been found that gases formed by arcing between the switch contacts will accumulate in the

hood in spite of the ventilating openings leading from the enclosed space to the atmosphere. These gases tend to increase the conductivity of the gap formed by the separation of the switch contacts and consequently the tendency to arcing is increased. In order to reduce this effect to a minimum, the exhaust air passage 33 from the regulating portion of the governor is connected to the space adjacent to the switch contacts, so that air is blown into the enclosed space when the cut-in piston 8 moves the valve 9 to its seat and opens communication for venting air from the switch piston 5 to the passage 33. Air thus supplied to the enclosed space tends to scavenge the same of the objectionable gases above referred to.

Having now described my invention, what I claim as new and desire to secure by Letters Patent, is:—

1. In an electric pump governor, the combination with a piston and stem carrying switch contacts, of a yielding contact adapted to engage each switch contact and having a hook at one end, a spring member secured to said yielding contact and bent to form an open ended loop with said contact, the end of the contact hook overlapping the end of said member, to thereby limit the lateral movement of said yielding contact. 90

2. In an electric pump governor, the combination with a piston and stem carrying longitudinally movable switch contacts, of a laterally movable yielding contact adapted to engage each switch contact and having a hook at one end, a spring member secured to said yielding contact, a support for said member, and a stop carried by said support and adapted to be engaged by the end of said hook for limiting the vertical movement of said yielding contact. 100

3. In an electric pump governor, the combination with a piston and stem carrying switch contacts, of a yielding contact adapted to engage each switch contact and having a hook at one end, a spring member secured to said yielding contact and formed to extend into said hook to thereby limit the lateral movement of said yielding contact, a support for said spring member, and a stop carried by said support and adapted to be engaged by the end of said hook for limiting the vertical movement of said yielding contact. 110

4. In an electric pump governor, the combination with a piston operated by fluid under pressure, a hollow stem carried by said piston, stationary contacts, and movable contacts carried by said stem for engaging the stationary contacts, of a port through said piston for supplying fluid under pressure to said hollow stem and ports opened upon movement of the piston by fluid under pressure for supplying fluid under pressure from said hollow stem to said contacts. 120

5. In an electric pump governor, the combination with a piston and switch contacts 10
operated thereby, of a regulating portion
having a cut-in piston operated upon move-
ment to the cut-in position for venting fluid
from the switch piston to the space adjacent
the switch contacts. 15
- 5 piston and operable upon movement to its
cut-in position for venting fluid from said
switch operating piston to a passage leading
to the space adjacent said switch contacts.
6. In an electric pump governor, the com-

In testimony whereof I have hereunto set
my hand.

CLYDE C. FARMER.
